EXHIBIT 3 E.C.M.

NO. 14,619

FED 5, 1884

UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A SCONCE-FRAME.

SPECIFICATION forming part of Design No. 14,619, dated February 5, 1884.

Application filed July 16, 1883. Term of patent 7 years.

To all whom it may concern:

Be it known that I, ALBERT PATITZ, of Meriden, in the county of New Haven and State of Connecticut, have invented a new Design 5 for a Sconce-Frame; and I do hereby declare the following, when taken in connection with the accompanying drawing and the letters of reference marked thereon, to be a full, clear, and exact description of the same, and which said 10 drawing constitutes part of this specification, and represents a face view.

This invention relates to a design for mirror-frames, such as commonly called "sconces;" and the design consists in the configuration 15 and ornamentation of the frame as shown in the accompanying illustration. The two sides of the frame are each composed of two parallel bars, leaving an open panel filled with a floriated tracery representing daisies. At the 20 top and bottom of each side is a square block,

on the face of which is the representation of a daisy. Between the two blocks at the top is a frame-work filled with floriated tracery representing daisies, this frame-work being preferably broader than the sides. The bottom is 25 composed of two bars corresponding to the sides, and like them ornamented representing daisies.

I claim—

The herein-described design for a sconce-frame, consisting of the sides, top, and bottom, composed of the open frame-work filled with a tracery representing daisies, and with the square block at the intersection of the sides, top, and bottom, as shown in the accompanying 30 illustration.

ALBERT PATITZ.
